Primary Examiner — Michael A. Pratt

(74) Attorney, Agent, or Firm — Winthrop & Weinstine, P.A.

(57) **CLAIM**

We claim the ornamental design for concealable firearm, as shown.

DESCRIPTION

FIG. 1 is an isometric view of a concealable firearm in an in-use position.

FIG. 2 is a front plan view of the concealable firearm depicted in FIG. 1.

FIG. 3 is a rear plan view of the concealable firearm depicted in FIG. 1.

FIG. 4 is a top plan view of the concealable firearm depicted in FIG. 1.

FIG. 5 is a bottom plan view of the concealable firearm depicted in FIG. 1.

FIG. 6 is a right side elevation view of the concealable firearm depicted in FIG. 1.

FIG. 7 is a left side elevation view of the concealable firearm depicted in FIG. 1.

FIG. 8 is a front plan view of the concealable firearm depicted in FIG. 1 in its stored position.

FIG. 9 is a rear plan view of the concealable firearm depicted in FIG. 8.

FIG. 10 is a top plan view of the concealable firearm depicted in FIG. 8.

FIG. 11 is a bottom plan view of the concealable firearm depicted in FIG. 8.

FIG. 12 is a right side elevation view of the concealable firearm depicted in FIG. 8; and,

FIG. 13 is a left side elevation view of the concealable firearm depicted in FIG. 8.
